DESIGN FOR A HEATER

Charles F. Gatons and Lawrence J. Hausser,
Joliet, and Herman H. Heidbreder, Quincy, Ill.,
assignors to The Moore Corporation, Joliet, Ill.,
a corporation of Delaware

Application January 27, 1938, Serial No. 74,590

Term of patent 3½ years

To all whom it may concern:

Be it known that we, Charles F. Gatons and Lawrence J. Hausser, citizens of the United States, residing at Joliet, county of Will, and State of Illinois, and Herman H. Heidbreder, a citizen of the United States, residing at Quincy, county of Adams, and State of Illinois, have invented a new, original, and ornamental Design for a Heater, of which the following is a specification, reference being had to the accompanying drawing, forming a part thereof.

In the drawing, the figure is a perspective view showing the front and one side of a heater embodying our design, the other side being substantially similar to the one shown.

We claim:

The ornamental design for a heater, as shown and described.
